(57) **CLAIM**

The ornamental design for a toothbrush head, as shown and described.

DESCRIPTION

FIG. 1 is a front perspective view of a toothbrush head, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the toothbrush head, which form no part of the claimed design. The dash-dash-dot lines illustrate the bounds of the enlarged view as well as the bounds of the portion of the drawing figure from which it was taken and form no part of the claimed design.
